UNITED STATES PATENT OFFICE.

LEOPOLD WESTON AND JOHN REID JONES, OF NORTHCOTE, AUCKLAND, NEW ZEALAND.

BILGE-PUMP.

1,305,508.

Specification of Letters Patent.

Patented June 3, 1919.

Application filed February 1, 1919. Serial No. 274,479.

To all whom it may concern:

Be it known that we, LEOPOLD WESTON and JOHN REID JONES, both citizens of the Dominion of New Zealand, and both residing at Rodney Road, Northcote, Auckland, in the Provincial District of Auckland, in the Dominion of New Zealand, have invented certain new and useful Improvements in Improved Bilge-Pumps, of which the following is a specification.

This invention relates to pumps used for pumping bilge water from ships and boats, and provides a pump which operates by the rolling of the vessel in which the same is installed.

The invention comprises a pendulum connected to the plunger of a pump proper, the end of the pendulum being provided with a friction roller adapted to run in a race and prevent the pendulum rod from being strained during the pitching of the vessel.

The drawing herewith illustrates the invention.

Figure 1, is a front elevation, and Fig. 2, a side elevation of the pump, and Fig. 3, is a sectional plan on line 3—3, Fig. 1.

The pendulum rod 1 and a lateral arm 2 are fixed to a shaft 3 mounted in a standard 4, which has a base 5 fixed to a deck or the frame of the vessel. The pendulum weight or bob 6 is adjustable on the rod 1 by a nut 7 screwed upon the said rod. A friction roller 8 mounted on the end of the rod 1 is adapted to run in a curved and grooved race 9, the center of which is coincident with the center of the shaft 3. The said race is disposed transversely of the vessel, and prevents the rod 1 from being strained by the weight 6 when the vessel pitches.

The pump proper 10 is fixed to the base 5 and the plunger 11 thereof is connected by a rod 12 to the arm 2. The suction pipe 13 is led down to the bilge of the vessel, and the delivery pipe 14 is led overboard above the surface of the water in which the vessel is floating.

When the vessel rolls, the force of gravity holds the pendulum vertically or approxi-

mately vertically, while the pump oscillates with the vessel, with the result that the cylinder of the pump 10 reciprocates on the plunger 11 and water is drawn from the bilge and forced overboard. The dotted lines in Fig. 1 shows the pump at its maximum oscillation in both directions, and the plunger 11 at its maximum reciprocation.

The stroke of the pump is adjusted by means of holes 15 provided in the arm 2, the end of the rod 12 being connected to the said arm by passing the pin 16 through any one of the said holes.

What we do claim and desire to secure by Letters Patent of the United States is:

1. A pump adapted to oscillate with the rolling of the vessel in which the same is fixed, a standard, a shaft journaled in the standard, a pendulum connected to the shaft, coercive means connected to the pendulum and adapted to be connected to the vessel for guiding the movement of the pendulum, a lateral arm fixed to the shaft, and a rod connecting the arm to the plunger of the pump, as set forth.

2. In a bilge pump the combination with a pendulum, of a roller operatively connected to the lower end of the pendulum and a curved and grooved race in which the friction roller is adapted to run.

3. A pump adapted to oscillate with the rolling of the vessel in which the same is fixed, a standard, a shaft mounted in the standard, a pendulum and a lateral arm fixed to the shaft, a friction roller mounted on the end of the pendulum rod, a curved and grooved race in which the friction roller is adapted to run, and a rod connecting the said arm to the plunger of the pump, as set forth.

In testimony whereof we have signed our names to this specification in the presence of two witnesses.

LEOPOLD WESTON.
JOHN REID JONES.

Witnesses:
